UNITED STATES PATENT OFFICE.

JOHN SIDNEY SCOTT, OF RICHMOND, VIRGINIA.

PUZZLE.

1,236,769.

Specification of Letters Patent.

Patented Aug. 14, 1917.

Application filed November 11, 1916. Serial No. 130,762.

To all whom it may concern:

Be it known that I, JOHN S. SCOTT, a citizen of the United States, residing at Richmond, in the county of Henrico and State 5 of Virginia, have invented certain new and useful Improvements in Puzzles; and I do hereby declare the following to be a full, clear, and exact description of the invention, such as will enable others skilled in 10 the art to which it appertains to make and use the same.

This invention relates to new and useful improvements in a puzzle and one of its objects is the provision of a device of this 15 character, which shall be simple, durable and efficient, and which may be manufactured and sold at a comparatively low cost.

Another object of this invention is to provide a pair of horseshoe-shaped members 20 connected together and having a substantially horseshoe-shaped member capable of sliding on either of the horseshoe-shaped members on which is mounted a ring to be removed from the horseshoe-shaped members 25 to solve the puzzle.

With these and other objects in view as will become more apparent as the description proceeds, the invention consists in certain novel features of construction, combination 30 and arrangement of parts as will be hereinafter more fully described and claimed.

For a complete understanding of my invention, reference is to be had to the following description and accompanying drawing, in which:

Figure 1 is a plan view of a puzzle, constructed in accordance with my invention,

Fig. 2 is a side elevation of the same,

Fig. 3 is a sectional view taken on the line 3—3 of Fig. 2 looking in the direction indicated by the arrows,

Fig. 4 is a similar view taken on the line 4—4 of Fig. 2 looking in the direction indicated by the arrows, and

Fig. 5 is a perspective view illustrating the manner in which the ring is removed from the horseshoe-shaped members.

Referring in detail to the drawing, the 50 numeral 1 indicates as an entirety a horseshoe-shaped member constructed from a continuous piece of wire bent upon itself and having each end bent to form eyes 2'. The

numeral 2 indicates a horseshoe-shaped member constructed from a continuous piece of wire having its leg portions passed through the eyes 2' of the horseshoe-shaped member 1 and bent to form eyes 3 for pivotally connecting the members 1 and 2 together. Secured to the leg portions of the member 2 55 is a slideable guard 4. A substantially horseshoe-shaped member 5 has its leg portions converging in the direction of each other and the ends thereof bent to engage the member 1 by forming eyes 6. A guard 60 7 is rigidly secured to the member 5 for aiding in preventing the puzzle from being solved. A ring 8 is mounted on the leg portions of the member 5 which is adapted to be removed from the member 5 and the 65 members 1 and 2 to solve the puzzle, which will be hereinafter more fully described.

To solve the puzzle, the member 5 is slid in the direction of one of the eyes of the member 1 as illustrated in Fig. 3. The 70 member 2 is then folded under the member 1 and the ring is slid or passed over the eyes 2' and 3 of the members 1 and 2 upon one of the leg portions of said members until the ring is free to slide upon the members 1 and 2 and be removed from the other end as illustrated in Fig. 3.

The guard 4 is slideable on the member 2 and will permit the ring to slide freely thereon.

From the foregoing description taken in connection with the drawing, it will be noted that a puzzle has been provided which is attractive, neat and ornamental in form and yet which will present a puzzle apparently impossible to solve.

While I have shown and described the preferred embodiment of my invention, it will be understood that minor changes in construction, combination and arrangement 90 of parts may be made without departing from the spirit and scope of the invention as claimed.

Having thus described my invention, what I claim is:

A puzzle comprising a pair of horseshoe-shaped members having their ends bent upon each other in the formation of eyes to pivotally connect said members together, a substantially horseshoe-shaped member having 105 its ends bent upon one of the horseshoe-

shaped members, a guard secured to said substantially horseshoe-shaped member, a guard slidably secured to one of the horse-shoe-shaped members, and a ring mounted on the substantially horseshoe-shaped member and adapted to be removed therefrom to solve the puzzle.

In testimony whereof I affix my signature in presence of two witnesses.

JOHN SIDNEY SCOTT.

Witnesses:

JOHN C. DABNEY,
OTTO U. GARDNER.
